UNITED STATES PATENT OFFICE.

VIRGINIUS Z. CARACRISTI, OF BRONXVILLE, NEW YORK.

VARIABLE EXHAUST NOZZLE FOR LOCOMOTIVES.

Application filed October 11, 1920. Serial No. 416,234.

To all whom it may concern:

Be it known that I, VIRGINIUS Z. CARACRISTI, a citizen of the United States, and a resident of Bronxville, in the county of 5 Westchester and the State of New York, have invented certain new and useful Improvements in Variable Exhaust Nozzles for Locomotives, of which the following is a specification.

10 This invention relates to an improved variable exhaust nozzle for locomotives and has for its primary object to provide a simply constructed adjustable nozzle of this type whereby the velocity of the steam is 15 suing from the nozzle orifice may be minutely regulated and controlled.

Generically considered, the present invention contemplates the provision of means whereby the area of the emission orifice of 20 the exhaust nozzle may be varied to increase or decrease the steam velocity and consequently the draft through the fire tubes of the locomotive boiler, as circumstances may require.

25 In the attainment of the above purposes, in one embodiment of the invention I propose to provide a series of axially adjustable blades or vanes within the exhaust nozzle operable in the emission orifice thereof and 30 of variable width so that in the adjustment of said vanes, they will occupy a greater or less proportion of the nozzle orifice whereby the steam velocity will be proportionately fixed or determined.

35 Generally my present improvement has for its purpose to provide a variable exhaust nozzle of this character which will be more efficient in operation for the proper variation of the nozzle steam blast velocity than 40 such nozzles as heretofore produced while at the same time, the nozzle construction is simple, not liable to get out of order and may be manufactured and installed in locomotives of the present types at nominal 45 cost.

With the above and other objects in view, the invention consists in an improved form, construction and relative arrangement of the several parts as will be hereinafter more 50 fully described, illustrated in the accompanying drawings and subsequently incorporated in the subjoined claims.

In the drawings wherein I have shown several practical and desirable embodiments 55 of the invention and in which similar ref-

erence characters designate corresponding parts throughout the several views;

Figure 1 is a vertical sectional view through a variable exhaust nozzle illustrating one embodiment of the invention. 60

Figure 2 is a plan view partly in section on the line 2—2 of Figure 1.

Figure 3 is a horizontal section taken on the line 3—3 of Figure 1.

Figure 4 is a fragmentary sectional view 65 similar to Figure 1 showing a slightly modified embodiment of the invention.

Figure 5 is a view similar to Figure 4, showing the adjustable blades or vanes in projected position to reduce the area of the 70 emission orifice and obtain an exhaust blast of high velocity.

Figure 6 is a horizontal sectional view taken on the line 6—6 of Figure 4.

Referring in detail to the drawings and 75 more particularly to Figures 1, 2, and 3 thereof, 5 designates the body of the exhaust nozzle which is bolted or otherwise secured at its lower end in the usual manner to a base plate or flange surrounding the steam 80 exhaust pipe connection to the smoke box of the locomotive. The upper portion of this body 5 is gradually tapered or reduced in diameter and is preferably provided with a detachable top section 6 having a flange 85 7 projecting longitudinally in relation to the nozzle axis and which flange defines the normal area of the steam emission orifice designated by the numeral 8.

The lower portion of the body 5 is bisected by a vertically extending web 9, preferably integral with the body walls. This web is centrally formed with vertically spaced longitudinally bored guides 10 and 11 respectively for rod or shaft 12. Between the 90 space guides 10 and 11 the web 9 is provided with a vertical slot 13, the opposite side faces of which are concave, as at 14, in concentric relation to the rod 12 which has sliding contact with said concave faces. The 95 rod or shaft 12 has a section of its exposed portion flattened on opposite sides thereof as at 15 and through this flattened section of the rod the transversely disposed bolt 16 extends. 100

One side of the nozzle body 5 is formed with a lateral bearing extension 17 having a pocket or recess 18 and rock shaft 19 extends through the pocket 18 thereof. Upon said rock shaft a pair of arms 20 are fixed 110

at one of their ends, said arms being located on relatively opposite sides of the vertical web 9 and having their other ends bifurcated or slotted as at 21 to receive the opposite ends of the bolt 16. Any suitable manually operable connection may be provided for the actuation of the rock shaft 19.

The upper end portion of the rod 12 extending above the guide bearing 10 is reduced in diameter and screw-threaded as at 22 to receive a head 23. This head carries diametrically opposed blades or vanes 24 which extend vertically through the upper nozzle section 6. Above the head 23, the inner edges of the blades or vanes 24 are obliquely inclined upwardly and outwardly as at 25. It is thus seen that each of these blades gradually tapers or decreases in width to its upper end. For the purpose of properly guiding the blades 24 in their vertical movement, in this embodiment of the invention I have shown the flange 7 provided with outwardly offset portions forming internal rectangular notches or recesses 26 in which the outer edges of the blades are engaged.

In Figures 4 and 5 of the drawings I have illustrated a slightly modified form of this guiding means wherein the head section of the nozzle body is provided below the emission orifice and at diametrically opposite points with the inwardly projecting lugs 27, each of which is formed with a notch or recess 28 to receive the outer edge portion of one of the blades. In this case, the vertical outer edge of the blade is slightly rounded or convex so that it will have proper sliding contact with the inner concave face of the flange 7.

In the operation of the nozzle, in either embodiment thereof above described, it will be understood that when the blades or vanes 24 are in the lowered position seen in Figure 1 or in Figure 4, the emission orifice 8 of the nozzle is of maximum area and the steam blast issues therefrom at relatively low velocity. When it is desired to increase the steam velocity in order to accelerate the passage of the products of combustion through the smoke box and the fire tubes, the rock shaft 19 is actuated, and through the medium of the arms 20, the rod 12 is moved upwardly. Thus the several blades 24 will also be moved upwardly in the exhaust nozzle, and the wider portions of said blades will be moved into the emission orifice, thereby reducing the effective area of said orifice and correspondingly increasing the velocity of the steam issuing therefrom. In this manner, an accurate variation in the velocity of the steam exhaust blast, through a considerable range may be obtained.

I have herein disclosed various alternative constructions of the invention, but it is also to be understood that the device might like-

wise be exemplified in numerous other mechanical embodiments and I therefore reserve the privilege of adopting all such legitimate changes in the form, construction and arrangement of the several parts as may be fairly embodied within the spirit and scope of the invention as claimed.

I claim:

1. A variable exhaust nozzle comprising a body having an emission orifice, and relatively adjustable means sub-dividing said orifice into a plurality of variable steam emission areas.

2. A variable exhaust nozzle having fixed and movable parts controlling the effective area of the nozzle orifice and means for adjusting the movable part to sub-divide the orifice into a plurality of variable steam emission areas.

3. A variable exhaust nozzle having fixed and movable parts, one of said parts being provided with means sub-dividing the nozzle orifice and means for adjusting the movable part to vary the effective steam emission area of the orifice.

4. A variable exhaust nozzle, comprising a body having a discharge orifice, and a discharge control member movable axially of said body and provided with a plurality of sections increasing in transverse area from their outer ends inwardly, engaging the orifice, and adapted to vary the steam emission area thereof.

5. A variable exhaust nozzle, comprising a body having a discharge orifice, a discharge control member movable axially of said body and provided with a plurality of sections arranged in spaced relation to each other, increasing in transverse area from their outer ends inwardly, engaging said orifice, and adapted to vary the steam emission area thereof, and means for operating said discharge control member axially of said body.

6. A variable exhaust nozzle having a body provided with an orifice, a plurality of members movable as a unit through said orifice and adapted to be positioned therein to vary the effective steam emission area of the orifice and means for actuating said members.

7. A variable exhaust nozzle including a body having an orifice, a rod axially movable within said body, a plurality of blades fixed upon the upper end of said rod, and having portions of varying width movable through said orifice, means operatively connected to said rod for positioning the blades in the orifice to thereby vary the effective steam emission area of the orifice.

8. A variable exhaust nozzle including a body, having an axially movable rod mounted in said body, diametrically opposed blades fixed upon the upper end, each having a tapering portion extending vertically

through the orifice, and means for actuating said rod to position said tapering blades in the orifice and thereby vary the effective steam emission area of the orifice.

5 9. A variable exhaust nozzle including a body having an orifice, an axially movable rod mounted in said body, a plurality of diametrically opposed blades fixed to the upper end of said rod and each having a

10 tapering portion extending vertically

through the orifice, guide means on the body wall receiving the outer edges of said blades, and means for actuating said rod to position the tapering portions of the blades in said orifice and thereby vary the effect of the 15 steam emission area of the orifice.

In testimony that he claims the foregoing as his invention, he has signed his name hereunder.

VIRGINIUS Z. CARACRISTI.
